UNITED STATES PATENT OFFICE.

ALEXANDER E. BROWN, OF CLEVELAND, OHIO, ASSIGNOR TO THE BROWN HOISTING MACHINERY COMPANY, OF CLEVELAND, OHIO, A CORPORATION.

COMPOSITE PILING.

SPECIFICATION forming part of Letters Patent No. 727,583, dated May 12, 1903.

Application filed December 5, 1902. Serial No. 133,954. (No model.)

To all whom it may concern:

Be it known that I, ALEXANDER E. BROWN, a citizen of the United States, residing in the city of Cleveland, county of Cuyahoga, and State of Ohio, have invented a new and useful Composite Piling; and I hereby declare the following to be a full, clear, and exact description of the same, reference being had to the drawings accompanying and making a part of this specification.

My invention belongs to the particular class of instruments or constructions of the kind referred to wherein the main constituent is cement, concrete, or like plastic material, sustained, however, and reinforced by combining the same either externally or internally with some other substance or material of a high degree of infrangibility. The employment of piles of this class in place of wood or metal is extremely desirable if certain defects in their construction, hitherto encountered, can be met and overcome, inasmuch as in the nature of things cement piling will not rot or be subject to the destructive action of worms, as in the case of woods, or to rust, corrosion, or other serious effects of water and moisture, as in the case of iron and other metals.

Heretofore, on occasions, piles have been made up of cement protected by an outer cylindrical casing of iron; but this casing being itself unprotected such piles are found liable to injury and deterioration from the same causes as piles made wholly of iron. So, too, when a concrete column has been supplemented by a timber core the relative difference in expansion and contraction of the two materials has proved a source of weakness, as well as the capacity and tendency of the wooden center to absorb moisture through its extremities.

My present invention is designed to afford a form of piling made up of concrete or like material firmly united and strengthened throughout its length by a metallic tube or cylinder uniformly related to said concrete at all points and which is itself wholly protected thereby. I accomplish said result by the peculiar combination shown in the drawings, and which I shall now point out with more detail.

In the drawings similar parts are indicated by the same characters of reference.

Figure I is a perspective view of a pile when broken crosswise, made according to my invention. Fig. II is a cross-sectional view of 55 such pile. Figs. III and IV are segmental views, respectively, of methods of making up the metal parts employed in my said construction.

A is a tubular core or cylinder of the same 60 length as the pile itself. It is characterized by a series of longitudinal corrugations c and d, whose cross-sections are claviform or dovetail in shape and may be made up by bending sheet-metal plates having the corrugations 65 just described into cylinders and then uniting the same to each other at their ends until the desired length for the piling is attained. When thus made up, the said material itself will be the same as that heretofore and separately invented by me and covered by United States Letters Patent dated December 17, 1901, and bearing No. 689,281. As will appear by reference to said patent, the corrugations referred to may either have cross-sections of the same dimensions throughout their 70 course or they may be given a taper in alternately-reversed direction with respect to each other, in such case presenting cross-sections of different dimensions in different parts of 75 the several corrugations. In Fig. III, I represent a portion of said core A when made up of a longitudinally-connected series of cylindrical pieces a and b, having corrugations of the same dimensions throughout their length, 80 and in Fig. IV a series of similar pieces a', having tapering corrugations with cross-sections of different dimensions. The latter pieces a', one with respect to another, will be alike in every particular, and manifestly will 85 telescope or overlap each other interchangeably and in this relation may be secured together. The former pieces, however, will not thus interfit, and to enable one to penetrate the other and to thereby be fastened together 90 through the overlapping portions I accordingly make the pieces a sufficiently larger in all dimensions than the intermediate pieces b to receive the same. It is of course evident that dovetailed corrugated pieces a and 95 b to receive the same. It is of course evident that dovetailed corrugated pieces a and 100

b may be employed of equal dimensions one with respect to the other and be fastened together without interpenetration end to end by riveting the same to a common internal 5 band or part at the point or in any other suitable manner. Said tubular core or cylinder having been formed, as indicated, the cement, mortar, concrete, or like suitable material is molded about and filled within the same, and 10 the construction is thereby completed.

In the drawings, C represents the concrete matter composing the piling that surrounds said core A, and C' the like matter that fills the same.

15 Although I show, describe, and, as a specific form of my device, claim a piling wherein the tubular portion A is made up out of metal or material corrugated, as described, both inside and out, yet it is evident that 20 while this form of construction has strong special advantages and, which will give it preference in practice my said invention in its broader scope is not to be limited to a form of structure only that is interiorly corrugated. 25 It is plain that in this sense the invention covers a pile wherein the cement or like material entering into its composition is held together and stiffened by a cylindrical core, although said core is substantially smooth with- 30 in, the essential characterization in such case

being supplied if said core is provided in any suitable manner with exterior claviform or dovetail-shaped corrugations of adequate proportions to receive and retain the outer coating C.

Having thus described my invention, what I claim, and desire to secure by Letters Patent, is—

1. A piling, composed of cement or like material, containing an internal longitudinal 40 tube or core, made up of a series of sheet-metal cylinders, fastened together at their ends, the said cylinders having claviform or dovetail-shaped corrugations lengthwise of the same, substantially as shown and de- 45 scribed.

2. A piling composed of cement or like material, containing an internal tube or core, made up of a series of sheet-metal cylinders having claviform or dovetail-shaped corruga- 50 tions, the said cylinders being arranged to overlap or telescope with each other, and, in such position to be riveted or otherwise fastened together at their ends, substantially as shown and described.

ALEXANDER E. BROWN.
